LUMINAIRE HOUSING

Dana Warren Mox, Glenview, Ill., assignor to Revere Electric Manufacturing Company, a corporation of Delaware

Filed June 8, 1964, Ser. No. 80,312

Term of patent 14 years

(Cl. D48—31)

FIGURE 1 is a perspective view of the luminaire housing, showing my new design, the broken line showing of the lens being for illustrative purposes only;

FIGURE 2 is a top plan view thereof;

FIGURE 3 is a front elevational view thereof.

I claim:

The ornamental design for a luminaire housing, substantially as shown and described.
